UNITED STATES PATENT OFFICE

2,668,343

CONNECTOR FOR WRIST WATCHES OR
ORNAMENTATIONKurt A. Rieth, Cranston, R. I., assignor to Speidel
Corporation, Providence, R. I., a corporation of
Rhode Island

Application September 15, 1950, Serial No. 185,042

6 Claims. (Cl. 24—265)

1

The principal objects of the present invention are to provide a connector which may be quickly and conveniently attached to and detached from a wrist watch, to provide a connector which can be made in any of a number of different shapes so as to harmonize with the wrist watch or ornamentation and the bracelet or band to which it is attached; and to provide a connector which is of simple but durable construction, reliable in operation, and capable of being economically manufactured.

Further objects will be apparent from a consideration of the following disclosure and the accompanying drawing, wherein:

Fig. 1 is a top plan view of my new bracelet or band with the sections in outstretched position;

Fig. 2 is a side elevation of the bracelet as it appears when being worn or displaced;

Fig. 3 is a longitudinal vertical section through one of the articulate sections shown in Fig. 1;

Fig. 4 is an enlarged longitudinal vertical section through one of the end connectors and associated unit or link;

Fig. 5 is a bottom view of the parts shown in Fig. 4;

Fig. 6 is a transverse vertical section adjacent to the free end portion of the connector link showing the coupling pin in locking position;

Fig. 7 is a view similar to Fig. 6 but showing the coupling pin in released or unlocking position;

Fig. 8 is an enlarged isometric of one of the articulated units or links; and

Fig. 9 is an exploded view of a pair of interconnected elements constituting the bottom walls of a pair of links.

The embodiment herein shown for the purpose of illustration comprises two articulate sections 1 and 2 each having an end connector 3 for attaching the section to a wrist watch or ornamentation 4, and a terminal link 5 through which extends a retractor strand or chain 6 for yieldingly urging the two sections toward each other so that they will tend to embrace the wrist of the wearer more snugly. Each of the sections 1 and 2 comprises a series of interconnected links or units 10 (Figs. 3, 4 and 8) of geometrically similar shape and of progressively decreasing size from the end connector 3 to the terminal link 5.

Each of the units 10 comprises a generally semi-cylindrical shell or tubular element having adjacent to its opposite end portions diametrically disposed apertures 11 and 12 (Fig. 8). The outer ends of the units are each formed

2

with an integral extension 14 having an upwardly extending arcuate lip 15, and the inner ends of the units are each formed with an inwardly directed arcuate lip 16 defining a mouth 5 for receiving the extension 14 and lip 15 of the adjacent unit when the links are assembled so that the apertures 12 of one unit are aligned by the apertures 11 of the adjacent unit, as shown more clearly in Fig. 3.

10 The bottom walls of the units 10 comprise dished elements 18 (Figs. 3, 4 and 9) which snugly fit between the longitudinal edges of the units and these units are formed with integral parts rolled to provide a central sleeve 20 at one end and a pair of spaced sleeves 21 at the other end, the construction and arrangement of parts being such that when the elements 18 are assembled within the shells or units 10, the sleeves 20 of each unit is aligned with the apertures 12 and the sleeve 21 is aligned with the apertures 11; and when the units are assembled, the sleeves 20 of one unit fit in the openings between the sleeves 21 of the adjacent unit so that a pintle 22 may be passed through the apertures and sleeves so as pivotally to interconnect the units, as shown in Figs. 2 to 5.

15 The surface contour of the units 10 and the shape of the depending lips 16 are such that the latter is at all times in contiguous relation to the former, regardless of the angular position of the units relative to each other, as indicated in Fig. 2, thus eliminating dirt-collecting openings, recesses, etc., and presenting a more attractive appearance. The inner end of each terminal link 5 is formed similar to the inner end of each unit 10, being provided with an integral extension 14 having an outstanding lip 15 (Fig. 3), but its outer end converges somewhat to form a small opening through which the retractor 20 chain 6 passes. Similarly the bottom wall of each terminal link 5 is formed at its inner end with spaced sleeves to interfit with sleeve 20 of the adjacent unit 10, but the outer end of the bottom wall is rolled, as indicated at 23 in Fig. 3, to provide a smooth continuous surface. In order to insure a smooth operation of the chain or strand 6 in moving back and forth within the sections, I provide a chain slide 24 which consists of a tapered strip of stainless steel 25 or other suitable material (Figs. 3, 4 and 6) extending from the innermost sleeve 21 to the rolled edge 23, the inner end being formed with a sleeve 25 (Figs. 4 and 5) which fits about the pintle 22 between the sleeves 21, thus anchoring the slide in position.

Each of the connector links comprises a shell or housing 30 having a surface configuration simulating that of two interconnected units, thus preserving the characterizing motif of the section. Each connector link has a bifurcated or spaced inner end 31 to receive the coupling loop of a wrist watch or ornamentation 4, and an outer end conforming generally with that of a unit 10, being formed with a depending lip 16 embracing the curved surface of the inner unit 10, as shown more clearly in Fig. 4. The bottom wall 32, of each connector snugly fits between the longitudinal edges of the shell 33 and is held in position by inwardly bent tabs 35 (Fig. 5) integral with the shell 30. The outer end 15 of the bottom wall terminates in contiguous relation to the sleeves 21 and 25 and the opposite end of the bottom wall is formed with an extension 33 (Figs. 3 to 5) which curves inwardly to merge with the bifurcated end 31 of the sleeve. 20

With the construction and arrangement of parts above described the connector 3, terminal link 4 and intervening units 10 of each section may be swung from a "stretched out" position, as shown in Fig. 1, to a "curled up" position, such as illustrated in Fig. 2, the swinging movement of each unit relative to the adjacent unit, being limited by the engagement of the outwardly extending lip 15 with the depending lip 16 which not only provides a stop, but also a closure element contiguous to and giving the appearance of merging with the surface of the adjacent unit regardless of their angular position.

The walls of the bifurcated end portion 31 are formed with aligned apertures 43 (Figs. 6 and 7) to receive a coupling pin 42, the aperture 40a (Fig. 6) on one of the outer walls being smaller than the other aperture so as to prevent the coupling pin 42 from being pushed therethrough. The end portion of the coupling pin 42 adjacent to the smaller apertures 40a is formed with a circumferential groove defining a locking shoulder 44 and a conical-like surface or cam element 45, as shown in Figs. 6 and 7. The very tip of the pin at the end adjacent to the shouldered portion is formed with a circular recess 47a (Fig. 4) to receive the pointed end of a pin or the like, by means of which the coupling pin 42 may be slid axially to unlock position (Fig. 7).

Secured to the bottom wall extension 33 by a rivet 46 is latch spring 48, one end of which is formed by a cam-like nose 47 (Fig. 6) and its outer end with a hooked locking finger 49. The design of the parts is such that when the coupling pin is in operative or locking position (Fig. 6), the cam-like nose 47 of the latch spring 48 engages the shoulder 44 and cam surface 45 and the finger 49 at the opposite end of the spring 48 is flexed outwardly by the plain end of the coupling pin 42. Hence, the coupling pin 42 may be slid from operative or locking position (Fig. 6), wherein it passes through the usual opening in the coupling member of a wrist watch or ornamentation, to the left by inserting a pin or the like pointed instrument through the apertures 40a into recess 47a, thereby forcing the grooved end to disengage the cam nose 47. Such axial movement is limited by the engagement of the locking finger 49 with the shoulder 44, as shown in Fig. 7, which prevents complete removal of the pin 42. When in released or unlocking position (Fig. 7) the coupling member of the wrist watch or ornamentation may be moved to and from a position between the bifurcated ends of the connector link, and coupling the 75

parts is merely a matter of moving the pin 42 to the right (Fig. 7) until the grooved end engages the marginal portions about the aperture 40a, in which position the cam nose 42 snaps into locking position.

Although the connector 3, terminal link 4 and intervening units 10 may be pivotally connected so that friction or other means holds them in one position or another, the retractor strand 6 is preferably employed yieldingly to urge the terminal links together. The retractor strand 6 may consist of any suitable flexible material such as a cord, chain or the like, one or both ends of which are connected to a retractor mechanism 50 (Figs. 3 and 4) operative to draw the strand or chain 6 inwardly, thus swinging the links or units 10 to curled position so that they embrace the wrist of the wearer with comfortable snugness.

The retractor 50 comprises a housing consisting of the interfitting plates 51, 52 and 53 (Fig. 4) which provide the outer and intermediate walls defining two chambers, the outer walls 51 and 53 being formed with integral lateral tabs by means of which the parts are held in position. 25 The three plates are formed with aligned openings to receive a suitable shaft 58 and secured to one part of the shaft 58 is one end of the retractor 6 (Fig. 3), the other end of which may be similarly secured to a retractor 50 or otherwise anchored in the other section of the bracelet. The inner end of a spiral watch spring 60 is anchored to another part of the shaft 60 and the other end of the spring is secured to one of the lateral flanges or tabs of the plate 51, the arrangement being such that the chain 6 is wound up about the shaft by the action of the spring 60. The entire assemblage 50 has a tight fit within the shell 30, as shown in Figs. 3 and 4, with retractor chain 6 passing through the units of one section to and through those of the other section.

It will be noted that with the construction and arrangement of parts herein shown and described a bracelet or band having end connectors 3 may be readily attached to and detached from a wrist watch or the like ornamentation and there is no danger of the coupling pin becoming accidentally dislodged. Moreover, the construction and arrangement of parts are such as to permit the ornamental shell to be made in various shapes so as to harmonize with the design of the watch and band.

While I have shown and described one desirable embodiment of the invention, it is to be understood that this disclosure is for the purpose of illustration and that various changes and modifications may be made without departing from the spirit and scope of the invention as set forth in the appended claims.

I claim:

1. A connector for a wrist watch or ornamentation having a coupling loop, which comprises a member having at one end spaced hollow parts having outer and inner walls and between which parts said coupling loop is received, said parts having aligned apertures in their outer and inner walls, a releasable coupling pin axially slidable within said apertures and extending from one of said parts to the other so as to pass through an interposed coupling loop, one end portion of said coupling pin having a circumferential groove shaped to provide a circumferential shoulder, a resilient latch member in one of said parts having a cam-like part engageable with said shoulder so as yieldingly to oppose

axial movement of said pin when in locking position, said cam-like part being movable out of engagement with said shoulder by pressure applied axially to said pin, and a locking finger in the other of said parts engageable with said shoulder for limiting the axial movement of said pin.

2. A connector for a wrist watch or ornamentation having a coupling loop, which comprises a member having at one end spaced hollow parts having outer and inner walls and between which parts said coupling loop is received, said parts having aligned apertures in their outer and inner walls, a releasable coupling pin axially slidable within said apertures and extending from one of said parts to the other so as to pass through an interposed coupling loop, one end portion of said coupling pin having a circumferential groove shaped to provide a circumferential shoulder, a resilient latch member in one of said parts having a cam-like part engageable with said shoulder so as yieldingly to oppose axial movement of said pin when in locking position, said cam-like part being movable out of engagement with said shoulder by pressure applied axially to said pin, means carried by one of said parts and engageable with said pin for opposing axial movement in one direction, and a locking finger in the other of said parts and engageable with said shoulder when said pin is slid to unlocking position so as to prevent complete removal of said pin.

3. A connector for a wrist watch or ornamentation having a coupling loop, which comprises a member having at one end spaced interconnected hollow parts having outer and inner walls and between which parts said coupling loop is received, said parts having aligned apertures in their outer and inner walls, a releasable coupling pin axially slidable within said apertures and extending from one of said parts to the other so as to pass through an interposed coupling loop, one end portion of said coupling pin having a circumferential groove, and a spring member extending within the interconnecting part with one end projecting into one of said parts so as to engage said circumferential groove and yieldingly oppose axial movement of said coupling pin when in locking position, said pin thereby being slidable into and out of locking position by pressure applied axially thereto and the other end of said spring member projecting into the other of said parts so as to engage said circumferential groove when said pin is slid to unlocking position and prevent complete removal of said pin.

4. A connector for a wrist watch or ornamentation having a coupling loop, which comprises a member having at one end spaced hollow parts having outer and inner walls and between which parts said coupling loop is received, said parts having aligned apertures in their outer and inner walls, the aperture in one of said outer walls being smaller than the others, a releasable coupling pin having adjacent to one end a recessed portion, said pin being axially slidable within said apertures from a locking position wherein said pin extends from one of said parts to the other and passes through an interposed coupling loop with the end adjacent to said recessed portion abutting the marginal portion surrounding

the smaller aperture, to unlocking position, wherein said recessed portion is within the other of said parts, and a latch member within the first mentioned part, said latch member having a cam-like part engageable with said recessed portion so as yieldingly to oppose axial movement of said pin from locking to unlocking position.

5. A connector for a wrist watch or ornamentation having a coupling loop, which comprises a member having at one end spaced hollow parts having outer and inner walls and between which parts said coupling loop is received, said parts having aligned apertures in their outer and inner walls, a releasable coupling pin axially slidable within said apertures and extending from one of said parts to the other so as to pass through an interposed coupling loop, one end portion of said coupling pin having a recess shaped to provide a shoulder, a resilient latch member in one of said parts having a cam-like part engageable with said shoulder so as yieldingly to oppose axial movement of said pin when in locking position, the aperture in the outer wall of said one of said parts being smaller than the end of said pin thereby to prevent axial movement thereof in one direction, and a locking finger in the other of said parts engageable with said shoulder when said pin is in unlocking position to limit axial movement in the other direction.

6. A connector for a wrist watch or ornamentation having a coupling loop, which comprises a member having at one end spaced interconnected hollow parts having outer and inner walls and between which parts said coupling loop is received, said parts having aligned apertures in their outer and inner walls, the aperture in one of said outer walls being smaller than the others, a releasable coupling pin having adjacent to one end a circumferential groove defining a shoulder, said pin being axially slidable within said apertures from a locking position, wherein said pin extends from one of said parts to the other and passes through an interposed coupling loop with the end adjacent to said shoulder in abutting relation to the marginal portion surrounding the smaller aperture, to an unlocking position, wherein said shoulder is within the other of said parts, and a resilient member having its body portion secured between said parts with one end extending into one of said parts to engage said shoulder and yieldingly oppose axial movement of said pin when in locking position, and the other end of said resilient member extending into the other of said parts to engage said shoulder when said pin is in unlocking position and prevent removal of said pin.

KURT A. RIETH.
